ATTACHMENT FOR CHECK CONTROLLED APPARATUS

Filed May 21, 1924

FIG. 1.

FIG. 2.

Inventor

Hugo E. Heyns

Cushman Bryant & Darby
Attorneys

UNITED STATES PATENT OFFICE.

HUGO E. HEYNS, OF CHICAGO, ILLINOIS.

ATTACHMENT FOR CHECK-CONTROLLED APPARATUS.

Application filed May 21, 1924. Serial No. 714,983.

To all whom it may concern:

Be it known that HUGO E. HEYNS, a citizen of the United States, residing at Chicago, in the county of Cook and State of Illinois, has invented new and useful Improvements in Attachments for Check-Controlled Apparatus, of which the following is a specification.

This invention relates to attachments for coin or check controlled machines, and has as its object the provision of means for indicating the number of coins deposited.

A further object of the invention is to provide an indicating device which may be cheaply manufactured and which may be readily associated with a coin receptacle.

The invention comprises broadly a member having means for mounting the same adjacent the inlet opening of a coin receptacle, the member being provided with a series of slots adapted to be brought into registry with the inlet opening and each slot having associated therewith some suitable means which will indicate the insertion of a coin therethrough. For this purpose a readily frangible sheet of material may be employed to close each slot, and the fracture of the sheet when the coin is inserted will indicate that the slot has been used.

In the accompanying drawings there is shown one embodiment of the invention, and in these drawings:

Figure 1 is a top plan view, and

Figure 2 is a section on the line 2—2 of Figure 1 showing the device properly positioned adjacent a coin box.

Referring to the drawings for a more detailed description, the attachment comprises a movable member, such as a disk formed from cardboard, metal or other suitable material, rotatably mounted upon a bracket arm 11 by means of a pivot pin 12. The bracket arm has a portion 13 provided with openings 14, through which may be inserted any suitable securing means to properly position the attachment adjacent the inlet opening 15 of a coin receptacle 16. The disk 10 is formed with a series of slots 17, which, preferably, are radially arranged in an annular series so that when the disk is moved the slots may be brought consecutively into registry with the inlet opening of the coin receptacle.

In association with each slot is suitable means for indicating the insertion of a coin

therethrough. This means may be, for example, glued or otherwise joined to the under-surface of the disk and a sheet 19 of material adapted to be readily fractured when a coin is inserted through any one of the slots into the receptacle opening.

In use, a person desiring to keep track of the number of coins deposited will properly position the attachment in the manner described, and each time a coin is to be inserted in the receptacle, will move the disk to bring another slot over the coin inlet opening. It is not necessary that automatic means be provided for moving the disk each time a coin is inserted, although such means may be employed if desired, since the device is useful for enabling one depositing the coins to keep a record of the number of coins he inserts in the receptacle.

It will be understood that the gist of the invention is a movable member, such as the disk 10, provided with means for positioning the same adjacent the coin inlet opening of a receptacle 11. Obviously, the disk must be located so that as the same is rotated, the slots 17 may be carried to a position over the coin inlet opening. It being understood that modifications may be readily made in the structure illustrated and described without departing from the invention, what I claim is:

1. A device of the class described comprising a member having a series of coin slots, means in association with each slot for indicating the insertion of a coin therethrough, and means adapted to support said member over the inlet opening of a coin receptacle, said supporting means permitting the member to be moved to bring said slots successively into registry with said opening.

2. A device of the class described comprising a member having a series of radially disposed coin slots therein, means in association with each slot for indicating the insertion of a coin therethrough, and a supporting device rotatably carrying said member and adapted to support the member over the inlet opening of a coin receptacle whereby the member may be moved to bring said slots successively into registry with said opening.

In testimony whereof I have hereunto set my hand.

HUGO E. HEYNS.
